UNITED STATES PATENT OFFICE.

HENRY SEIBEL, OF LOS ANGELES, CALIFORNIA, ASSIGNEE TO UNITED AIR SPRING COMPANY OF ARIZONA, OF PHOENIX, ARIZONA, A CORPORATION OF ARIZONA.

PNEUMATIC SEAT.

1,286,446.

Specification of Letters Patent. Patented Dec. 17, 1918.

Application filed December 4, 1917. Serial No. 205,442.

To all whom it may concern:

Be it known that I, HENRY SEIBEL, a citizen of the United States, residing at Los Angeles, in the county of Los Angeles, and 5 State of California, have invented new and useful Improvements in Pneumatic Seats, of which the following is a specification.

My present invention is a modification of the invention shown, described and 10 claimed in my companion application filed May 7th, 1917, for pneumatic seats, Serial No. 167,026; the object of my present invention being to simplify and improve the details of construction of the supporting casing and make the parts quickly detachable 15 for inserting or removing the inner pneumatic tube, and my invention consists in the novel features herein shown, described and claimed.

20 Figure 1 is a side elevation showing the pneumatic seat embodying the principles of my invention and applied to a motorcycle frame.

Fig. 2 is an enlarged fragmentary view on 25 a plane parallel with Fig. 1 partly in elevation and partly in section.

Fig. 3 is a plan of the attaching ring to which the pneumatic supporting casing is vulcanized.

30 Fig. 4 is a perspective of the metallic parts by which the supporting casing is connected to the seat frame.

Fig. 5 is a view analogous to Fig. 2 and showing a modified construction.

35 Fig. 6 is a fragmentary perspective of the metallic parts by which the supporting casing is connected to the seat frame in Fig. 5.

The casing binding ring 1 is circular upon 40 its periphery 2 and has a concentric opening 3 and tapped bolt holes 4. The inner edge of the ring is rounded and the outer edge of the ring is tapered and slightly curved downwardly in cross-section. The supporting casing 5 is normally spherical and has an 45 opening corresponding to the opening 3 in the ring 1. The ring 1 is placed in position with the portion 6 of the casing extending through the opening 3, the portion 7 of the material extending outwardly over the ring, 50 and the portion 8 extending outwardly beyond the ring and vulcanized to the body of the casing. After the casing has been thus

prepared, openings 9 are formed through the portion 6 to register with the bolt holes 4, which are here shown as four in number, 55 but any number may be used, as desired.

The fitting 10 comprises the central tubular portion 11; the passage through the portion 11 being the same size as the passage through the portion 6 of the casing; a supporting base 12 extending outwardly from the lower end of the tubular portion 11 and adapted to press upon the portion 7 of the casing in opposition to the ring 1, the casing guard 13 extending outwardly and upwardly 60 from the base portion 12, and the attaching flange 14 extending outwardly from the upper end of the tubular portion 11.

The attaching plate 15 may be circular in 65 plan for one supporting casing or it may be of any desired form where a plurality of casings are to be used. The attaching plate 15 has a central opening 16 the same size as the passage through the portion 6 of the casing and the tubular portion 11, and the flange 14 fits against the lower side of the plate around said opening. Bolts 17 are inserted downwardly through the plate 15 and through the flange 14 to hold the fitting 10 rigid with the attaching plate 15, and 70 bolts 18 are inserted downwardly through the attaching plate 15 and through the flange 14, through the base 12, through the portion 7 of the casing, and are screw-seated in the bolt holes 4 in the ring 1, care being taken 75 that when the bolts 18 are screwed down tight the points of the bolts will not extend through the ring 1.

The attaching plate 15 is secured to the main seat frame 19 by bolts 20. The main 80 seat frame 19 has a chamber 21 communicating through the throat, formed by the opening 16, the tubular portion 11 of the fitting 10 and the opening through the portion 6 of the casing, with the chamber 22 85 in the supporting casing 5. A pneumatic inner tube 23 is mounted in the chamber 21 and has an extension 24 extending through the throat into the supporting casing 5.

The parts are made up as described to the 90 bolts 20, the inner tube is placed in the chamber 21, then the extension 24 is inserted through the throat into the casing 5, the attaching plate brought into position against 95

the seat frame 19, and nuts applied to the bolts 20. The bolts 20 are studs rigidly fixed in the seat frame 19 and in assembling the parts these studs are passed through the bolt holes 25. The casing guard 13 forms a rounded surface against which the casing 5 operates, and the softer the casing 5 becomes or the greater the load, the more the guard will be engaged by the casing.

10 When it is desired to remove the inner tube, the nuts are unscrewed from the stud bolts 20 and the attaching plate 15 pulled away from the seat frame, the inner tube having been deflated, and the extension 24 15 pulled out of the casing 5.

Referring to the modification shown in Figs. 5 and 6, the seat frame 26 is similar in construction to the seat frame 19, and the attaching plate 27 and the parts 28, 29, 20 30 and 31 are similar to the parts 15, 11, 12, 13 and 14 in Fig. 2. Bolts 32 connect the flange 31 to the attaching plate 27 and bolts 33 are inserted downwardly through the attaching plate 27 through the flange 31 25 and screw-seated in the supporting base 29. The metallic binding ring 34 has an upwardly sloping rounded inner face 35 and a downwardly sloping rounded outer face 36. This metallic ring is placed inside of 30 the casing 37 around the opening 38 in opposition to the attaching base 29, and the parts are vulcanized to secure the ring 34 against the inner face of the casing and the attaching base 29 against the outer face of 35 the casing in opposition to each other.

Projections 44 extending upwardly from the ring 34 press the material of the casing 37 into recesses 45 as in the attaching base 29, so as to produce rough and uneven surfaces for the vulcanized rubber to unite with and stick to and to assist in gripping the casing and holding it from pulling out from between the two metallic parts.

In building and assembling the parts, the 45 ring 34, the casing 37, and the attaching base 29 are first vulcanized together, then the bolts 32 are inserted to secure the attaching plate 27 to the flange 31, the bolts 33 are inserted to still further secure the 50 parts together, then the inner tube 39 is placed in the chamber 40 in the seat frame 26 and the extension 41 of the inner tube is inserted downwardly through the tube 28 into the casing 37, then the nuts 42 are 55 applied to the stud bolts 43.

The seat frame 19 or 26 constitutes a frame having a chamber with an opening at one side, and the casing 5 or 37 constitutes a cover for the opening, said cover 60 forming an extension of the chamber in the frame and said cover being larger than the opening.

While the casing is situated to primarily receive the shock and sustain the load, the 65 chamber in the frame constitutes a reservoir

and an additional cushion and prevents a perceptible increase of the air pressure in the casing.

The guards 13 and 30 serve to protect the inner tube from getting squeezed and to hold the casing in place when the inner tube is more or less deflated.

The conical deformer 45 is mounted upon the base 46 in vertical alinement with the opening 47 through the neck and tends to turn the casing inside out under a heavy load or when deflated. The action of the deformer serves to keep the fabric under tension instead of compressing or wrinkling the contacting portion as on a flat surface.

The pneumatic support thus constructed was primarily intended for use upon a motorcycle seat, as shown and described in my companion application before mentioned, and in such use there would be preferably two of the supporting casings and co-operating parts. It is obvious, however, that a single supporting casing may be used or that any desired number may be used in combination and that the members may be applied anywhere that a shock absorbing or elastic action is desirable, such as in supporting engines, supporting vehicle bodies, in aeroplane work, mattresses, shock absorbers, and the like.

Various changes may be made in the details of construction without departing from the spirit of my invention as set up in the following claims.

I claim:

1. In a pneumatic seat, a ring having tapped bolt holes, and a spherical casing having an opening smaller than the opening through the ring and having material extending through the opening of the ring over the ring and vulcanized to its body.

2. In a pneumatic seat, a metal ring having tapped bolt holes, a casing vulcanized to the ring, a fitting having a tubular portion matching the opening from the casing through the ring, a supporting base in opposition to the ring, and a flange extending from the upper end of the tubular portion, an attaching plate fitting against the flange, and bolts inserted downwardly through the attaching plate, through the flange, through the base and through the material of the casing into the tapped bolt holes of the ring.

3. In a pneumatic seat, a metal ring having tapped bolt holes, a casing vulcanized to the ring, a fitting having a tubular portion matching the opening from the casing through the ring, a supporting base in opposition to the ring, and a flange extending from the upper end of the tubular portion, an attaching plate fitting against the flange, bolts inserted downwardly through the attaching plate, through the flange, through the base and through the material of the cas-

ing into the tapped bolt holes of the ring, and a casing guard extending upwardly and outwardly from the base.

4. In a pneumatic seat, an attaching plate 5 having bolt holes and a central opening, a fitting having a tubular opening matching the central opening in the plate, a supporting casing having a metallic ring embedded around an opening matching the opening 10 through the tubular portion of the fitting and having tapped bolt holes, and bolts inserted downwardly through the attaching plate into the ring.

5. In a pneumatic seat, an attaching plate 15 having a central opening, a fitting having a tubular opening matching the central opening in the plate and having a flange extending from its upper end, a pneumatic casing having a ring embedded around an opening 20 matching the tubular opening in the fitting and bolts inserted through the attaching plate and through the flange to hold the fitting rigidly in place relative to the attaching plate.

25 6. In a pneumatic seat, an attaching plate having a central opening, a fitting having a tubular opening matching the central opening in the plate and having a flange extending from its upper end, a pneumatic casing 30 having a ring embedded around an opening matching the tubular opening in the fitting, bolts inserted through the attaching plate and through the flange to hold the fitting rigidly in place relative to the attach-

ing plate, and bolts inserted downwardly 35 through the attaching plate through the flange and into the ring.

7. In a pneumatic support, a spherical 40 pneumatic casing having an opening, a binding ring inside of the casing around the opening, and an attaching base against the casing around the opening and in opposition to the binding ring; the base, casing and binding ring being vulcanized together.

8. In a pneumatic support, a pneumatic 45 casing having an opening, a binding ring inside of the casing around the opening, projections upon the binding ring against the casing, and an attaching base against the outside of the casing in opposition to the 50 binding ring and having recesses in opposition to the projections; the binding ring, casing and base being vulcanized together.

9. In a pneumatic support, a metallic frame 55 having a chamber and an opening leading to the chamber, means forming a neck having a throat leading from the chamber, an attaching base extending outwardly from the outer end of the neck, a spherical pneumatic casing fitting against the attaching base and 60 having an opening communicating with the throat, and a binding ring inside of the casing around the opening; the binding ring, casing and attaching base being vulcanized 65 together.

In testimony whereof I have signed my name to this specification.

HENRY SEIBEL.
